CLAIM

The ornamental design for a toy car, as shown and described.

DESCRIPTION

FIG. 1 is a front, right and top perspective view of a toy car, showing my new design;

FIG. 2 is a rear, left and bottom perspective view thereof; FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 of FIG. 1 thereof;

FIG. 10 is an enlarged view of portion 10 of FIG. 1 thereof;

FIG. 11 is an enlarged view of portion 11 of FIG. 1 thereof;

and,

FIG. 12 is an enlarged view of portion 12 of FIG. 2 thereof. The broken lines shown in the drawings illustrate portions of the toy car that form no part of the claimed design.

The dot-dash-dot broken lines in FIGS. 1, 2, 9, 10, 11, and 12 depict boundaries of the detailed enlargement that form no part of the claimed design.

1 Claim, 12 Drawing Sheets
